HEAT TREATING APPARATUS

Theodore W. Munford, Ottawa Hills, Ohio, assignor to General Properties Company, Inc., Toledo, Ohio, a corporation of Delaware

Application January 6, 1943, Serial No. 471,515

3 Claims. (Cl. 211—113)

This invention relates to apparatus for heat treating metal articles and more particularly to apparatus for suspending the articles in a furnace chamber.

The article supporting apparatus comprises an overhead support and article supporting hangers depending therefrom and it is an object of the invention to provide a hanger which shall comprise a number of readily detachable similar link bars of a form and construction well adapted to stand repeated heating and cooling or quenching. Other related objects will more fully appear from the detailed description taken in connection with the accompanying drawings wherein the preferred form of the invention is shown.

In the drawings—

Fig. 1 is a vertical section of a furnace of the type with which the present invention has special utility, the view also showing the article supporting apparatus or fixture of the present invention.

Fig. 2 is a plan view of the top of the article supporting fixture and a plan view of that portion of the furnace which supports said fixture.

Fig. 3 is a fragmentary detail view on line 3—3 of Fig. 2.

Fig. 4 is an enlarged side elevation of a portion of the apparatus of the present invention.

Fig. 5 is a section on line 5—5 of Fig. 4.

Fig. 6 is a view corresponding to Fig. 5 except that the parts are shown in different position.

Fig. 7 is a perspective view of one of the parts shown in Figs. 5 and 6.

The type of furnace with which the present invention has special utility comprises an upright open-ended shell 10 inside of a furnace chamber formed by a bottom wall 11, side walls 12 and a removable top 13. A fan 14 between the bottom wall 11 and the lower end of the shell draws heating gases through the shell, the gases being heated by contact with heating elements 15 between the shell and the side walls 12 of the furnace, it being understood that the gases are recirculated in a flow path which includes the space between the shell and the side walls 12 and that the shell constitutes the chamber wherein the articles are placed for heating.

In accordance with the present invention, the articles (not shown) that are to be heated in the shell 10 are suspended therein by a removable fixture generally indicated at 16 and comprising an overhead support 17 from which a plurality of articles supporting hangers depend into the shell. Loading and unloading of the fixture will, of course, be done outside of the furnace and the articles will be secured to the hangers as by

hooks or the like, not shown, passed through apertures 18' in the hangers.

The overhead support 17 is of open work construction (see Fig. 2) so as not to substantially impede the flow of gases therethrough and in its preferred form comprises a plurality of laterally spaced beams 19 maintained in spaced relation by spacers 20 through which tie rods 21 extend for holding the beams together. Each of the beams is adapted to support a row of the hangers 18, the hangers being detachably secured to a depending web of the beams by connecting pins 22.

In accordance with the present invention, each 15 of the hangers 18 is comprised of a series of link bars 23 each having a jaw 26 at one end and a tongue 27 at its other end for insertion in the jaw of the next succeeding link bar for coupling therewith by means of a pin 28. The number of 20 hangers used at any one time and the number of link bars in any one hanger will depend on the shape and size of the articles to be heated. Thus if the articles to be heated are bulky, it 25 may be that only a few hangers with only a few bars in each will be required to properly support the articles whereas if the articles are relatively small so that many articles can be accommodated in the shell 10 then it may well be that all of the hangers will be employed either in full length 30 or part length as may be required to properly support the articles.

In accordance with the present invention each 35 pin 28 for coupling a mating jaw and tongue has a radial extension 29 midway its ends and each jaw has axially-aligned radially-elongated pin-receiving apertures 30 which will permit the pin with its extension to be passed therethrough. Also each tongue has a radially-elongated pin-receiving aperture 31 which will permit the pins 40 with its extensions to be passed therethrough. The primary function of the extension 29 is to hold the pin in place in the jaw and tongue apertures 30 and 31 without the use of other retaining means such as cotter pins or the like, this 45 function being accomplished by first positioning the extension in the tongue aperture to point away from the tip of the tongue as shown in Fig. 6 with the result that when the hanger is under tension (see Figs. 4 and 5) the sides of the jaw will prevent the pin from being removed. When the parts are in the position shown in Fig. 6 the pin can, of course, be readily removed by axial displacement from either end thereof.

From the foregoing it will be readily appreciated that because the various hangers 18 are

each made up of a series of loosely articulated link bars, any distortion in the link bars as a result of repeated heating and quenching has very little effect on their usability and moreover in case any link bar should eventually fail as a result of repeated heating and quenching it is a simple matter to replace it with a new bar. As clearly shown in Fig. 4, it is preferred that the apertures 18' be of the same shape and size as the tongue aperture 31 so that in case the bar must be shortened from its tongue end (as in the case of damage), the outermost aperture 18' will constitute a ready made new tongue aperture 31.

What I claim is:

1. A hanger for supporting articles from an overhead support, comprising, in combination, a jaw, a tongue for insertion in said jaw, said jaw and tongue constituting the adjacent ends of similar link bars, and a pin adapted to be received in apertures in the jaw and tongue for pivotally connecting them, said pin having a radial extension intermediate its ends and said apertures being oblong to permit the pin with its extension to be passed therethrough regardless of whether the extension faces up or down, said extension when the pin is in position in said apertures for coupling the jaw and tongue being positioned in the aperture in the tongue in a direction away from the tip of the tongue whereby when the hanger is under tension the extension will be confined in the tongue aperture by the sides of the jaw whereby to hold the pin in place in said apertures.

2. In apparatus of the class described, the combination with an overhead support, of a plu-

rality of article supporting hangers depending therefrom, said hangers each comprising a jaw, a tongue for insertion in said jaw, said jaw and tongue constituting the adjacent ends of similar link bars, and a pin adapted to be received in apertures in the jaw and tongue for pivotally connecting them, said pin having a radial extension intermediate its ends and said apertures being radially elongated to permit the pin with its extension to be passed therethrough regardless of whether the extension faces up or down, said extension when the pin is in position in said apertures for coupling the jaw and tongue being positioned in the aperture in the tongue in a direction away from the tip of the tongue whereby when the hanger is under tension the extension will be confined in the tongue aperture by the sides of the jaw whereby to hold the pin in place in said apertures.

3. As an article of manufacture, a hanger link comprising a bar having at one end an oblong hole for a coupling pin and having at its other end a jaw adapted to receive the first mentioned end of an identical link bar and having between said jaw and said hole a row of oblong holes of substantially the same size as the first mentioned hole and said jaw having a pair of aligned oblong holes of substantially the same size as the first mentioned hole whereby a connecting pin that can be passed through the said aligned holes can also be passed through any of the other holes in an identical bar.

THEODORE W. MUNFORD.
